UNITED STATES PATENT OFFICE

EDWARD L. CARROLL, OF DETROIT, MICHIGAN, ASSIGNOR TO DUNBAR D. MACMECHAN
AND HAROLD E. YOUNG, BOTH OF DETROIT, MICHIGAN

PACKAGE

Application filed August 8, 1927. Serial No. 211,586.

This invention relates to packages and more particularly to a golf tee package.

The invention has as its primary object to provide a package capable of holding golf tees and the like which is simple in construction and which as a consequence may be economically manufactured so that the same may be distributed as an advertising novelty, the cover of the package providing ample space 10 for the display of advertising matter.

The several objects, advantages and novel details of construction of my invention will be made more apparent as this description proceeds, especially when considered in connection with the accompanying drawings 15 wherein:

Figure 1 is a perspective view of a package constructed in accordance with this invention.

Figure 2 is a vertical sectional view 20 through the package.

Figure 3 is a transverse sectional view taken substantially on the plane indicated by line 3—3 in Figure 2, and

Figure 4 is an end elevational view of a 25 modified form of construction.

While the cover of the package may be made of any desired material it is preferably made of cardboard, pasteboard or heavy paper and is formed of a strip 10 folded to 30 form a back 11, a top 12, a front 13 and a bottom 14. The bottom is extended upwardly a short distance to form a flap 15 and when the package is closed the lower edge 16 of the front is inserted behind the upper edge of the 35 flap 15 as most clearly shown in Figure 2.

Located within the cover is a member 17 formed with a plurality of apertures or pockets for receiving the golf tees or other articles. This member may be conveniently 40 formed of a sheet of corrugated material and is secured within the cover by having its lower edge stapled between the flap 15 and back 11 by means of a staple 18. The corrugations of this corrugated sheet provide a plurality 45 of pockets 19 into all or selected ones of which the golf tees T may be inserted. The construction of tee holding member 17 is preferably such that a substantial portion of the stem of the golf tee is received therein.

50 Located on opposite sides of the member

17 and adjacent the openings of the pockets 19 are strips 20 of corrugated material. These strips may be secured to the member 17 in any desired manner as, for instance, by gluing the same thereto and the corrugations thereof are preferably crushed slightly, these strips acting as cushion members between the front and back of the cover and the articles carried in the pockets 19. Thus as seen most clearly in Figure 2 these cushion strips space 55 the rear and front walls 11 and 13 of the package from the golf tees and prevent the walls of the package from being pressed against the articles therein contained. 60

Obviously if the device is used as an advertising novelty, advertising matter may be printed, lithographed or otherwise suitably produced on the outsides of the package, particularly the front and rear thereof. The device lends itself to economical production in 65 large quantities so that it would be practical to distribute the package without cost as an advertising novelty. 70

In Figure 4 there is illustrated a slightly modified form of construction wherein a twin 75 package is provided, the structure illustrated in Figures 1 to 3 being duplicated and arranged with their backs 11 secured together, as by gluing, stapling or the like. With such an arrangement the top 12 of one package 80 will be diametrically opposed to the top of the other package.

While the details of construction of the device have been illustrated and described herein quite fully it will be apparent to those 85 skilled in the art that minor changes may be resorted to without departing from the spirit and scope of this invention and to this end reservation is made to make such changes as 90 may come within the purview of the accompanying claims.

What I claim as my invention is:—

1. In a package of golf tees, a cover, a pocketed member located within said cover 95 and providing a plurality of uniformly spaced pockets, the golf tees being supported in said package with the stems thereof extending within said pockets and the heads thereof overlapping and arranged alternately 100

in different planes whereby a plurality of golf tees may be compactly supported.

5 2. In a golf tee package, a cover, a member provided with a plurality of golf tee receiving apertures, each adapted to receive the stem of a golf tee and to support the same, the distance between said apertures being less than the size of the golf tee heads, said golf tees engaging in said apertures to different depths whereby to position the heads in staggered relation.

10 3. In a golf tee package, a cover, and an apertured member within said cover and connected thereto and providing a plurality of uniformly spaced apertures, the golf tees being supported in said package with the stems thereof extending into said apertures, the heads of the golf tees successively engaging said member and one another to position the heads in different planes whereby a plurality of golf tees may be compactly supported.

15 In testimony whereof I affix my signature.
EDWARD L. CARROLL.
